UNITED STATES PATENT OFFICE.

DAVID J. BOLDUC, OF SAN FRANCISCO, CALIFORNIA.

METAL HAIR TUBE.

Application filed February 23, 1927. Serial No. 170,360.

The present invention relates to a metal hair tube of the class used in connection with permanent waving machines.

In many instances in the modern hair dressing parlors, and similar establishments, the permanent waving machines such as use electric heaters, require tubes of various types for steaming the hair.

Some operators use paper tubes saturated with water or other liquid, others use metal foil rolls, or crude metal tubes with ordinary caps and in most instances, these tubes are very clumsy, waste much time, and are otherwise inconvenient.

15 In the majority of the processes followed, the tubes are sealed at the top and bottom with strings or special tools, so that the tube will retain a required amount of steam, during the steaming process.

20 Then too, in many of these cases, the tubes that are used, are only of a temporary nature, and are destroyed after each operation, thus making the process comparatively expensive.

25 Having in mind these difficulties, I have evolved and produced what I believe to be an exceptionally novel tube for the purpose, wherein the construction is such as to insure efficient performance, one which will 30 fulfill the requirements of a device of this class, and one which is believed to be a worthwhile achievement in mechanical efficiency.

35 Other advantages and features will become apparent from the following description and drawings.

In the drawings:—

Figure 1 is an elevational view of a hair tube, constructed in accordance with the present invention, showing the manner in which it is used, and constructed in accordance with the present invention.

Fig. 2 is a longitudinal section through the same.

45 Fig. 3 is a cross section taken approximately upon the plane of the line 3—3 of Fig. 1.

Fig. 4 is a perspective view of the inner section of the tube.

50 In its preferred form, the invention comprises a tube constructed of aluminum or other suitable metal, the same comprising an inner section 5, and an outer section 6, these sections being telescopically connected together. On one side, the inner section 5 is formed with a longitudinal entrance slot

or opening 8. Then at the open end and on one side of this slot, is formed with a cut-out portion or notch 9. The outer section 6, on the other hand, comprises a relatively short sleeve closed at the end 10, and open at the opposite end.

This outer sleeve section is also formed with a longitudinal entrance opening 12 adapted to register with the aforesaid opening 8. In addition, it is provided at one end with a notch 13 adapted to cooperate with the aforesaid notch or cut-away portion 9. These two notches cooperate in forming a hole through which the strands of hair 14 70 pass.

In using the device, the hair as is usual, is wrapped around the pin 16. Then the pin with the hair wrapped thereon is inserted into the improved tube. In order to do this, it is necessary to turn sections 5 and 6 so that the openings 8 and 12 are in registry with each other.

Having done this, the tubes are rotated to close the opening, and to permit certain of the strands of hair to extend out through the cooperating notches 9 and 13 as represented in Fig. 1. Preparatory to wrapping the hair and inserting the pin and the hair, it is of course saturated with appropriate liquid, and after the steaming process is finished, the sections are rotated with respect to each other to open the tube, and to allow the hair and pin to be easily withdrawn.

From the foregoing description and drawing, it will be seen that I have evolved and produced a novel hair tube which can be used over and over again, thus providing a time and labor saver and reducing the expense of the operator of a permanent waving establishment. The structure is characterized by the advantages already pointed out, and by the additional advantages of rapidity and smoothness, and rapidity of manipulation.

Persons familiar with inventions of this class will undoubtedly be able to obtain a clear understanding of the same and for this reason a more lengthy description is thought unnecessary.

Minor changes in shape, size and re-arrangement of parts may be resorted to within the scope of the adjoined claims.

Having thus described my invention, what I claim as new is:—

1. As a new product of manufacture, a hair steaming tube of the class described

comprising a pair of telescopically connecting relatively rotatable sections, having entrance slots adapted to be brought into registry, after which the sections may be turned upon each other for closing the openings and completing the steaming process.

2. As a new product of manufacture, a hair steaming tube of the class described comprising a pair of complementary telescopically connected tubular sections having entrance slots adapted to be brought into registry with each other for introduction of the hair to be treated and to be turned in directions away from each other to enclose the hair within said sections.

3. As a new product of manufacture, a

hair steaming tube of the class described comprising an inner tubular section closed at one end and open at its opposite end, said section being formed adjacent said opposite end with a notch, and on one side with a longitudinal entrance slot, an outer tubular section into which the inner section telescopes, said last named section being also provided on one side with an entrance slot adapted to register with the first-named slot, being closed at one end, said closed end co-operating with the open end of said inner section.

In testimony whereof I affix my signature.

DAVID J. BOLDUC.
